UNITED STATES PATENT OFFICE.

WILLIAM E. BYRNES, OF CLEVELAND, OHIO.

DESIGN FOR A RUBBER ELBOW.

SPECIFICATION forming part of Design No. 29,983, dated January 10, 1899.

Application filed December 2, 1898. Serial No. 698,115. Term of patent 14 years.

To all whom it may concern:

Be it known that I, WILLIAM E. BYRNES, a citizen of the United States, residing at Cleveland, in the county of Cuyahoga and State of Ohio, have invented and produced a new and original Design in Rubber Elbows, of which the following is a specification, reference being had to the accompanying drawings, forming part thereof.

Figure 1 is a plain elevation of my new design as it appears in readiness for the market. Fig. 2 is an end elevation thereof, looking in from the left of Fig. 1.

In its essential aspects the design is comprised in its general contour or appearance and as it addresses itself to the eye in Fig. 1. This view shows the article as it goes to the trade and comprises the elbow-shaped tube

A, of practically plain outline and perceptibly larger at the end *a* than at the opposite end *b* and ornamented at its smaller end by a decorative portion B, and two distinctly different circular portions C and D, lying between the portion B and the extremity *b* of the elbow, the whole constituting my new and original design.

What I claim is—

The design for a rubber elbow, substantially as shown and described.

Witness my hand to the foregoing specification this 27th day of November, 1898.

WILLIAM E. BYRNES.

Witnesses:

II. T. FISHER,
R. B. MOSER.
